US0D1043358S

(12) United States Design Patent (10) Patent No.: US D1,043,358 S
(45) Date of Patent: * Sep. 24, 2024

(54) BOTTLE

(71) Applicant: Homecourt Inc., Santa Monica, CA (US)

(72) Inventors: Courtney Cox, Malibu, CA (US); Sarah Jahnke, Dallas, TX (US); Nick Axelrod-Welk, Los Angeles, CA (US)

(73) Assignee: Homecourt Inc., Santa Monica, CA (US)

() Term: 15 Years

(21) Appl. No.: 29/883,224

(22) Filed: Jan. 25, 2023

(51) LOC (14) Cl. 09-01

(52) U.S. Cl. USPC D9/685
